THREAD PACKAGE WOUND FROM CONTINUOUS FILAMENTS OF A SYNTHETIC LINEAR POLYMER

Sidney Goddard, Abersychan, Pontypool, England, assignor to British Nylon Spinners Limited, Pontypool, England

Filed Mar. 6, 1956, Ser. No. 569,852

Claims priority, application Great Britain Mar. 17, 1955

5 Claims. (Cl. 242—176)

The present invention relates to thread packages wound on bobbins from drawn continuous filaments of a synthetic linear high polymeric substance showing visco-elastic properties, such as nylon. That is to say the invention is concerned with the shape and formation on a bobbin of the mass of such drawn filaments. These filaments, although capable of being stretched somewhat and resuming their original length, only do so over a period of time, rather than more or less instantaneously, and, after the drawing operation in which they are produced, they relax slowly from the length to which they have been stretched, to a length slightly, but significantly, less than the former length. It is the normal practice to wind such filaments, whether as single filaments, known as monofilaments, or as groups of twisted filaments, known as multifilaments, on to a rotating core, usually cylindrical in shape, which for convenience, but not limitation, will be known herein as a bobbin. The filaments are traversed axially of the bobbin by means such as a traveller revolving within the ring of a reciprocating ring-rail, and the movements of the traverse mechanism during the time of winding govern the shape of the wound package on the bobbin. Normally, such filaments are wound into cylindrical packages or into packages with a tapering extremity or extremities, depending on what further processes are to be performed on the filaments. For instance, if it is desired subsequently to unwind the filaments over one end of the bobbin, it will be desirable to have the shape of the package at that end tapered. Furthermore, the existence of the tapered end-portion of the package obviates the necessity for a flange at that end of the bobbin thus reducing the cost of the bobbin and precluding any of the difficulties inherent in winding thread satisfactorily between two flanges. If both end-portions of the package are tapered nothing more than a cylindrical tube is required as a bobbin, which is a considerable saving when the number of bobbins under consideration runs into millions, and no alignment of the traverse mechanism with the bottom flange is necessary in this case. Thus it will be seen that a satisfactory single or double-taper package is not only an attractive proposition from the economic point of view, but also attractive from the point of view of the simplicity of the winding and unwinding operations.

With drawn continuous filaments of a synthetic linear high polymeric substance showing visco-elastic properties, however, we have found that it may occur that, owing probably to the compressive force exerted after a drawing operation by the wound loops of filaments on to those loops beneath them and ultimately on to the material of the bobbin, a difference in shape of the parts of the wound package can bring about a difference between the physical characteristics of the filaments (e.g. degree of residual relaxation) in those respective parts. This feature is one which had not been met before the advent of these filaments of synthetic linear high polymeric substances such as nylon, which retract somewhat slowly but with great force on the bobbin on which they are wound after the drawing (or stretching) operation has been per-

2

formed on them to orient the filaments to increase their tenacity. The phenomenon will arise, if, as is normally the case to bring about the formation, there are less layers of yarn at the tapered end-portions of the package than in the middle body portion, because, then, filaments at a given same distance from the bobbin surface will be compressed by a different amount depending on whether they are in the body or end-portion of the package, owing to the differing number of layers of filaments outside them.

10 This phenomenon of the differing physical characteristics of the filaments in different parts of the wound package can be sufficient to prejudice the acceptance of such filaments in certain uses. For instance, the differences in relaxation brought about by the phenomenon may be most undesirable. This is particularly the case with filaments of nylon which have been wound in the normal manner, at the end of the drawing operation, by means of a reciprocating ring-rail working in conjunction with a plurality of rotating vertical spindles carrying bobbins,

15 wherein the upper end-portions of the wound packages are tapered by causing the ring-rail to traverse continuously over the body portions of the packages, but only in cycles over the upper end-portions in such manner that the nearer the noses of the packages are approached the

20 less coils are wound. Such a formation is readily brought about by a succession of gradually increasing and gradually decreasing strokes of the ring-rail, the stroke never falling below a certain datum marking the tops of the body portions of the packages, and rising to momentary

25 maxima in each cycle, marking the noses of the packages. It will be apparent in this formation that, over a given length of filament wound during the completion of a traverse stroke, the compressive forces experienced by the filament will vary according to its position in the package,

30 i.e. whether in the body portion or in the tapered end-portion. Such length of filament is comparatively short, and is such that, when the filament is pirned directly from the bobbin and used as weft in a woven fabric, the differences in the physical characteristics of parts of it give rise

35 to visible differences in lustre in the fabric, due to differential relaxation, which take the form of intermittent lines or bars, where the fabric is tighter than at other parts, known as weft barré. The insertion of a fairly high degree of twist before pirning will reduce this effect, but such

40 high twist is not always desired in weft yarns and in any case, it demands that an extra operation be performed.

Heretofore, therefore, the use of single- or double-taper packages of oriented nylon filaments has only been possible at the expense of fabrics with lustre differences

50 which are really unacceptable in certain uses, such as fabrics for high-class garments.

We have now, having elucidated the probable cause of the phenomenon, devised a manner of winding continuous filaments of a synthetic linear high polymer on to bobbins, such that any variations in the physical characteristics of those filaments brought about by winding, are rendered substantially innocuous so far as their effect on fabrics made from the filaments is concerned.

The present invention comprises a process of winding 60 yarn, consisting of a single filament or a plurality of filaments of a synthetic linear high polymeric substance showing visco-elastic properties, immediately after a drawing operation has been performed on the yarn, wherein the yarn is wound into a package on a bobbin 65 whose winding surface is of substantially cylindrical shape by means providing a gradually increasing traverse stroke from a minimum stroke at the start of winding, to a maximum stroke at the completion of winding such that the taper angle at a tapered end of the bobbin as herein-defined does not at any time during winding exceed 70 30°. The invention also comprises packages so wound, in which either or both end-portions of the package are

tapered. The taper angle at a point on an end-portion of the package is defined as the angle between a plane tangential to, or lying along, the surface of the end-portion of the package at the point, and a plane parallel to the axis of the bobbin and normal to that plane which includes both the said axis and the said point. The measurement of this angle is a convenient manner in which to define and limit the degree of taper allowable in a package before sloughing of the loops of yarn on the tapered portions may occur. If sloughing occurs, difficulty will be experienced in unwinding, even supposing that it is possible at all. The maximum taper angle at any time during winding is specified above, as it is probable that the surface of a tapered end-portion of the package will be made up of parts of varying degrees of curvature, but it is the maximum angle at any point and at any time, which is critical for stability. Parts of the tapered portion may, in fact, be convex, and parts concave; and the taper angle will almost certainly always vary during the winding, at different stages thereof.

It is also, of course, true to say that the minimum taper angle (measured after winding has proceeded sufficiently for such to be measured with any accuracy) that is essential for the most beneficial results to be obtained from the invention will also be a relevant consideration. However, in practice, as it is always desirable to wind the maximum amount of yarn in a package, it is clear that there will be no incentive to wind packages with very small taper angles, e.g. of the order of less than 10°. If it is attempted to wind a full package starting with such a small taper angle, however, it must be made clear that difficulty with sloughing will almost always occur, as it will be necessary to so steepen the angle of the nose in order to accommodate the required amount of yarn that the angle will, at some point, exceed 30°.

The preferred limits of taper angle can be stated to be 15° to 20°.

The invention makes it certain that the whole of each layer of filaments (save for the outermost layer) wound is covered by an equal number of further layers of filaments, so that any variations in the physical characteristics of the filaments do not occur within a layer i.e. in relatively short lengths of the filaments.

Furthermore, we have found that any differences between the physical characteristics of filaments lying nearer the inside of the package and those lying nearer the outside of the package, although not so detrimental to the use of the filaments, may largely be obviated by winding the filaments on to a bobbin fitted externally with a compressible sleeve or on to a bobbin which is itself made of a material considerably more compressible than a metal. This expedient will also ensure that filaments wound next to the surface of the bobbin can contract equally to those wound upon other layers of filaments. The present invention, therefore, further comprises a method of winding yarn, consisting of a single filament or a plurality of filaments of a synthetic linear high polymeric substance showing visco-elastic properties, immediately after a drawing operation has been performed thereon, wherein the yarn is wound into a package on a bobbin the winding surface of which is substantially cylindrical in shape and is made of compressible material, by means providing a gradually increasing traverse stroke as hereinbefore described; and also comprises packages so wound in which either or both end-ports are tapered.

The following description given with reference to the accompanying drawings demonstrates how the invention can be carried into effect.

Figure 1 is a diagram showing how yarn is conventionally wound after drawing.

Figure 2 is a diagram showing how yarn may be wound according to the invention.

Figure 3 is a diagrammatic view of a tapered end portion of a package wound according to the invention.

In Figure 1, the bobbin B is one having a single flange

F at the base thereof. Yarn Y is wound on the cylindrical portion of the bobbin between the flange and a point below the cap C of the bobbin, the upper end of the package being tapered at T. The figure shows how the 5 traverse varies throughout the winding, the upper limit of the traverse stroke varying between a and b according to regular cycles x of the traverse.

In Figure 2, a similar bobbin is shown with yarn wound upon it with a traverse which gradually increases from a stroke a at the beginning of the winding to a stroke b at the completion of the package.

In Figure 3, the overlapping of succeeding layers of 10 yarn is shown and two taper angles, θ_1 and θ_2 are shown for different points on the tapered nose portion during the 15 winding. This figure is partially sectioned, to illustrate a wood center 10 in bobbin B, enclosed by a compressible rubber sleeve 12.

Where synthetic linear high polymeric substances are 20 referred to above, it must be made clear that this expression is used to describe not only homopolymers, but also co-polymers and inter-polymers, which can be formed into fibres and filaments, and which are produced as a result of chemical synthesis. Examples of such polymeric substances are nylon and "Terylene" (Reg. T.M.) polyester 25 fibre.

The means to provide the gradually and progressively increasing traverse stroke may be of the general kind well-known in the textile art, suitably modified, and the 30 increase of stroke may either be at a constant rate or a rate varying with the length of the stroke. Similarly, the 35 time of each traverse stroke may be constant throughout the whole winding, or it may be varied with the length of the stroke, for example, proportionally to the same. Again the rate of traversing may be non-uniform throughout a stroke; for instance, the traverse may be accelerated at the points of reversal of direction.

Should it be desired to use a compressible sleeve, it 40 may be of the order of 30 thousandths of an inch to 200 thousandths of an inch thick, and it must not be too easily compressed by the strong filaments nor so hard that the filaments make little impression on it, or it will not have the desired effect. Certain types of hard rubber and cardboard have proved satisfactory, and a combination of hard and more compressible rubber in a 45 sleeve, with the former on the outside to prevent embedding of the first layer or layers of filaments, is eminently suitable. A maple bobbin has been found suitable for use as a bobbin of more compressible material than that of say, aluminium.

It is often desired to insert a low degree of twist, say 50 up to 7 turns per inch, to the yarns of the invention, and this will further assist in neutralising any differences in the yarn such as might cause barre.

Example 1

Continuous filaments of 205 denier nylon multifilament yarn, with a twist of $1/2$ turn per inch, were wound, after the spun filaments had been drawn 400%, on to a 55 cylindrical bobbin $1\frac{1}{4}$ inches in diameter with a flange 60 at one end thereof. The winding was effected by means including a reciprocating ring-rail working in combination with a spindle, carrying the bobbin, vertically mounted within a ring of the ring-rail, and rotating at 7,500 r.p.m. The yarn was led on to the bobbin through a 65 traveller free to rotate around the ring. The ring-rail was so reciprocated at a constant time cycle of 24 seconds that the traverse stroke imparted by it started at a length of 5 inches, with the bottom of the stroke corresponding to the point on the bobbin just above the 70 flange at the bottom thereof, and gradually increased in length throughout the duration of the winding of the package to a maximum length of $8\frac{1}{2}$ inches, the increase being uniform such that each layer of yarn overlapped by the layer beneath it by a constant small amount at the top end of the stroke. When completed, the over-

all diameter of the package was 2.9 inches, and the maximum taper angle of the tapered portion was 23°. The single-taper package so wound was quite stable, and the yarn was substantially free from any relatively short-length variations in physical characteristics such as would produce visible barré in a fabric containing the yarn in the weft. Fabric woven from the yarn which had been subsequently twisted to 5 turns per inch was completely free from barré.

Example 2

The same yarn as in Example 1 was drawn at a ratio of 4.8 and at a speed of 425 ft./min. and wound up at a spindle speed of 5,100 r.p.m. The traverse stroke increased uniformly, as in the previous example, from an initial length of 5 inches to a length of 7½ inches, during which time a package weighing 1 lb. was produced having a taper angle of 17° for the conical nose portion.

Example 3

45 denier nylon continuous filament yarn was drawn at a ratio of 3.31 and at 1,250 feet/min. and was wound up at a spindle speed of 7,600 r.p.m. according to Example 1, save that the traverse stroke was increased from 5 inches to 7½ inches and that the ring-rail was traversed in 20 second cycles. A 1 lb. package of yarn was thus produced with a conically tapering nose portion having a taper angle of 16° 48'.

Example 4

60 denier nylon multifilament yarn was drawn at a ratio of 3.17 and at 625 feet/min. and was wound up at a spindle speed of 6,000 r.p.m. according to Example 1, save that the traverse stroke was increased from 5½ inches to 7¾ inches during winding, and that the ring-rail was traversed in 10 second cycles. A 1 lb. package of yarn was produced with a conically tapering nose portion having a taper angle of 15°.

In the above Examples 2 to 4 the propensity of the

yarn to exhibit barré in fabric woven from it was reduced to below the visual level in a dyed fabric, and this despite the fact that the yarn was woven as weft in its substantially untwisted (½ turn per inch) condition.

- 5   What I claim is:
1. A yarn package consisting of a bobbin and a drawn single filament or a plurality of drawn filaments of a synthetic linear high polymeric substance showing visco-elastic properties wherein superposed layers of loops of the yarn are wound upon said bobbin substantially immediately after the yarn is drawn, each layer extending by a small amount beyond the preceding layer at either or both ends of the package; said package containing at least one pound by weight of yarn and wherein the axial distance on said bobbin covered by the longest layer of loops of yarn is not substantially greater than 1½ times the axial distance covered by the shortest layer.
  2. The package defined in claim 1 wherein the taper angle is between about 15° and 20°.
  3. The package defined in claim 1 wherein the surface of the bobbin on which the yarn is wound is defined by a compressible sleeve.
  4. The package defined in claim 1 where the surface of the bobbin on which the yarn is wound is made of a material more compressible than aluminum.
  5. The package defined in claim 1 wherein the taper angle at the ends of said package does not exceed 30° for any layer of the package.
